UNITED STATES PATENT OFFICE.

GEORGE E. RIDER, OF KANSAS CITY, MISSOURI.

BALING-PRESS.

1,143,318.

Specification of Letters Patent. Patented June 15, 1915.

Application filed July 7, 1913. Serial No. 777,642.

To all whom it may concern:

Be it known that I, GEORGE E. RIDER, a citizen of the United States, residing at Kansas City, in the county of Jackson and State of Missouri, have invented certain new and useful Improvements in Baling-Presses, of which the following is a specification.

This invention relates to baling presses and one of my objects is to produce a driving mechanism for the press of as few parts as possible arranged compactly and in a manner to afford easy and thorough lubrication.

It is also my object to provide a simple means for connecting this driving mechanism with a drive for propelling the baling press vehicle when desired.

Both of these driving mechanisms are so designed as to occupy practically no more space than a single drive shaft.

A further object is the provision of a door for controlling the feed opening from the hopper into the press to be operated automatically in time relation to the plunger.

With these objects in view the invention consists in the novel and peculiar construction and arrangement of parts hereinafter described and claimed; and in order that it may be fully understood reference is to be had to the accompanying drawings, in which—

Figure 1, is a vertical section through the press, the same being taken along the line I—I of Fig. 2, looking in the direction of the arrow. Fig. 2, is a broken side view of a portion of the press. Fig. 3, is a vertical section along the line III—III, looking in the direction of the arrow, on Fig. 2. Fig. 4, is a detail on an enlarged scale showing in elevation a portion of the feed door drive. Fig. 5, is a side view of a part of the press driving mechanism, being partly in section along the line V—V of Fig. 1. Fig. 6, is a vertical longitudinal section through the middle portion of the press. Fig. 7, is a horizontal section through the lower portion of the feed hopper. Fig. 8, is a detail in horizontal section showing the operative position of one of the clutch throwing means.

Referring to the drawings, the apparatus comprises the usual press frame 2, providing a baling chamber 4 in which operates a plunger 6 for carrying the material as fed through the feed opening 8 into the forward portion of the baling chamber where it is retained by the usual retainers 10 upon the

back stroke of the plunger. In the present case the feed opening is formed in one side of the press and communicates with the hopper 12. The plunger is equipped with a tail sheet or apron 14 which closes the feed opening when the plunger is forward of said opening, so as to guard against any material being fed in behind the plunger. Thus the material may be fed into the hopper at any time so far as the plunger is concerned. The plunger is connected by a link 16 to the lower end of an oscillating lever 18, the upper end of which is pivotally mounted between brackets 20 carried by the press. This lever is provided with a longitudinal slot 22 within which operates the roll 24 of a crank formed by a pair of arms 26 having hubs 28 journaled in the lower portions of brackets 20 and spaced apart by a sleeve 30, the free ends of the arms having a pin 32 for journaling said roll.

The lever 18 is also formed with a transverse slot 34 intersecting the slot 22 to provide clearance for the sleeve 30, during the oscillation of the arm.

For operating the crank, power is taken from a pulley 36 which is loosely mounted upon a shaft 38 journaled within the hubs 28 and sleeve 30. This pulley is arranged to be moved by a link 40 and lever 42 into clutching relation with a reducing gearing which is of well known principle and mounted within a housing 44. This housing is internally geared as shown at 46, to cooperate with a series of planetary gears 48 which in turn mesh with gears 50 rotating about the axis of the shaft 38. The outer one of the gears 50 is provided with a clutch hub adapted to be clutched with the pulley 36 while the remaining gears 50 are formed on disks 52 which are also provided with bosses 54 forming trunnions for the gear wheels 48. The outer disk is also provided with an additional boss 56 diametrically opposite its gear wheel in order to balance it since this disk rotates faster than the remaining ones of the series. The gear wheels and disks are held in assembled relation by means of a spring 58 surrounding the hub of the outer gear 50 and bearing at one end against the housing 44 and at its other end against a plate 60 which is also carried by said hub and bears flatly against the outer face of the adjacent gearing. The inner disk is provided with clutch jaws 62 adapted to engage with corresponding jaws 64 formed

on the adjacent hub 28, said jaws being held normally clutched under the influence of the spring 58.

It will be understood that power is transmitted from the pulley 36 through the gearing described to the crank at a speed corresponding to the ratio of the gearing 48—50, which gearing can be changed to substitute a different ratio to suit the requirements of the particular engine supplying the power. Besides shielding the gear from foreign matter or from accidental contact with the workmen, the housing forms a reservoir for the heavy oil 66 whereby the gearing is kept continuously and thoroughly lubricated.

On the opposite side of the press, the shaft 38 has journaled thereon, a pair of mutilated gear wheels 68, with their hub portions clutched together and the hub of the inner wheel also clutched with the adjacent hub 28 on one of the crank arms 26. These wheels are adapted to drive intermittently a beveled pinion 70 on the adjacent end of the shaft 72 mounted in bearings 74 on the press frame.

The shaft 72 is designed to be oscillated at the proper times for opening and closing the door 76 which in one position closes the opening 8 while the plunger is passing and in open or raised position allows the material to be fed into the hopper 12 ready to be carried in through the door opening into the baling chamber by the door when the same is again closed. This door is provided with arms 78, the upper ends of which are fixed to the shaft 72. While the plunger is traveling past the door the latter is held locked by means of a pivoted catch 80 which is held by a spring 82 in locking position and with one portion of the catch immediately behind one of the side margins of the door as clearly shown in Fig. 7. When in operative position a nose portion 84 of the catch projects within the baling chamber into the path of the plunger and as soon as the latter has traversed the door opening it engages said nose portion and swings the catch out of operative position so that the door will be free to swing under the action of the gear wheels 68.

The bevel pinion 70 is provided with a shroud plate 86 which just spans the distance between the outer margins of the wheels 68 and thereby cooperates with the catch 80 to lock the door when the latter is closed. Each of the wheels 68 is provided at proper intervals with peripheral notches, a short notch 88 adjacent its toothed portion 90 and a long notch 92 diametrically opposite notch 88. The wheels are so clutched together that the notch 92 of each wheel will be opposite the toothed portion of the other wheel, and so arranged that as the wheels, which are continuously rotated in the direction of the arrow, see Fig. 4, come into a po-

sition where one of the toothed portions 90 is about to engage with pinion 70, one corner of the shroud 86 will have just reached the end of the notch 92 of the opposite wheel and be free to turn into said notch while 70 the diametrically opposite corner of the shroud will be free to turn into the adjacent notch 88, which will have advanced sufficiently to permit this turning movement of the shroud. The dotted lines in Fig. 4 show 75 diagrammatically two stages of the shroud's movement after the same has started to rotate through the turning of the pinion, from which it will be obvious that the notch 92 must be longer than the opposite notch in 80 order to permit the shroud to turn through a half revolution.

It will be understood that after the shroud has been thus turned, the wheels 68 continue to rotate without affecting the pinion 85 70 and the door 76 is held stationary until the wheels have moved through another half revolution when a similar operation as regards the pinion and shroud takes place only in reverse order due to the reverse arrangement of the notches 86 and 92 and the toothed portion 90 at the opposite sides of said wheels, thereby swinging the door in the opposite direction.

As it may be desirable at times to propel 95 the truck of the press by means of the power applied to the pulley 36 I provide for this by securing a sprocket wheel 94 to the end of the shaft 38 which carries the wheels 68. This shaft, it will be understood, is normally 100 stationary, the other driving elements which have been described being merely loosely mounted thereon. When not driving the baling mechanism, I arrange to unclutch the same by throwing out the inner disk 52 from 105 engagement with the adjacent hub 28 and engaging the hub of said disk with a key 96 secured to the shaft. This action is caused to take place in opposition to the spring 58 by means of a bail 98 the ends of 110 which are pivoted to cranks 100 secured to the outer ends of a pair of short rock shafts 102 mounted in the housing. The inner ends of the rock shafts are provided with cams 104 which engage and slide the inner disk 115 52 when the bail is lifted thereby simultaneously unclutching the baling mechanism and clutching said gearing with the shaft 38 for operating the truck drive. The sprocket wheel is intended to drive a chain 120 106 to be suitably connected with a driven element, not shown, associated with the rear axle of the truck.

It is thought that from the foregoing the operation of the apparatus will be clearly 125 understood. To briefly summarize, the operation is as follows; power is transmitted from the pulley 36 through the gearing 48—50 at a reduced speed to the crank which operates the lever 18; as the roll moves through 130

the lower end of the slot 22, the lever 18 is advanced to give the plunger its forward stroke, the door 76 being meanwhile locked and the wheels 68 turning freely by the 5 shroud 86 without turning the pinion 70.

When the plunger has passed the door opening, it trips the catch 80 preparatory to the opening of the door. As the roller 24 emerges from the lower half of the slot 10 22, the plunger attains its maximum compression stroke just prior to which the door has started to open through the operation 15 of the mutilated gears. As soon as the door has risen sufficiently to open the hopper the latter may be filled with the material to be baled which will be carried into the baling chamber upon the next downward movement 20 of the door. The plunger is retracted by the movement of the roll 24 through the upper portion of the slot 22 and it will be observed that this being that portion of the slot which lies adjacent to the pivot of the link 18, the plunger is given a quick backward throw requiring little power while the 25 forward working stroke of the plunger takes place while the roll is within that portion of the slot, which, while it moves the plunger more slowly, gives a longer arm whereby to exert greater power on the plunger. 30 The catch 80 operates automatically, being always returned by the spring 82 to normal locking position after the passage of the plunger in either direction and after the return of the door to closed position, it being understood the door on closing turns 35 the catch on its pivot in the same direction as it is turned by the forward movement of the plunger.

All further operations of the baling mechanism are the same as that already described, but when it is desired to stop the machine, the rod 40 will be operated to throw the pulley 36 out and thereafter the machine may be self-propelled by lifting 40 the bail 98 which will unclutch the gearing 45 49-50 from the baling mechanism and clutch it with the pulley 36 as well as with the shaft which drives the sprocket drive connected with the rear axle of the truck. 50

At the intersection of the slots 22 and 34 an angle piece 108 is pivoted to the lever 18 in such a way that the lower arm of the angle will bridge the slot 34 and afford a track for the roller 24 as the latter passes 55 from one end of the slot 22 to the other. When the roller 24 is in the upper end of slot 22, it engages the upper arm of the angle piece 108 and thus swings the lower arm of said angle piece up out of the slot 34 to permit the lever 18 to move and allow the shaft to enter the left end of the said slot 34. 60

From the foregoing it will be apparent that I have produced a baling press embodying the features of advantage enumerated as desirable, and I wish it to be under-

stood that while I have illustrated and described one embodiment of the invention, I reserve the right to all modifications falling within the spirit and scope of the appended claims.

I claim—

1. In a baling press, a baling chamber provided with a door opening, a plunger mounted to reciprocate within said chamber past said opening, a door for controlling 75 said opening, means for intermittently opening and closing said door, and means acting automatically to lock the door when the same is closed, said locking means being adapted to be tripped by the plunger in its advance stroke to unlock said door.

2. In a baling press, a baling chamber provided with a door opening, a plunger mounted to reciprocate within said chamber past said door opening, means for driving 85 said plunger, a door for controlling said opening, a shaft provided with a pinion for operating said door, and mutilated gearing connected with said driving means and adapted to cooperate with said pinion for intermittently closing and opening said door in timed relation with the plunger.

3. In a baling press, a baling chamber provided with a door opening, a plunger mounted to reciprocate within said chamber 95 past said opening, means for driving said plunger, a door for controlling said opening, a pair of mutilated gear wheels connected with said driving means, and a shaft provided with a pinion and shroud located 100 in cooperative relation with said gear wheels, said pinion being adapted to be intermittently driven by said wheels for opening and closing the door, and said shroud cooperating with the gear wheels to lock 105 said shaft and door during the intervals of rest of said pinion.

4. In a baling press, the combination of a plunger, a crank for driving the plunger, a driving member rotatable about the same 110 axis as said crank, and means interposed between said member and crank for transmitting power from the former to the latter at a reduced speed.

5. In a baling press, the combination of a 115 plunger, a crank for operating said plunger, a pulley, and speed reducing gearing for transmitting power from said pulley to said crank, said crank, pulley and gearing all operating about a single axis transverse to 120 the press.

6. In a baling press, a baling chamber provided with a door opening, a plunger mounted to reciprocate within said chamber past said opening, means for driving 125 said plunger, a door for controlling said opening, a shaft and pinion for operating said door, means for intermittently engaging and rotating said pinion, a drive pulley, and means interposed between said pulley 130

and plunger driving means for transmitting power from the former to the latter at a reduced speed, said pulley, power transmitting means, plunger driving means and 5 pinion rotating means all operating about the same axis.

7. In a baling press, the combination of a baling chamber, a plunger mounted to reciprocate within said chamber, an oscillating lever for driving said plunger, said lever having a longitudinal slot and a transverse slot intersecting the longitudinal slot, a shaft mounted in the path of movement of 10 the transversely slotted portion of the lever,

a crank arm carried by said shaft and provided with a roller adapted to travel in said longitudinal slot, and an angle piece pivoted on said lever near the intersecting portions of said slots in position to be engaged by said roller and moved to intermittently 15 bridge the transverse slot.

In testimony whereof, I affix my signature, in the presence of two witnesses.

GEORGE E. RIDER.
